CLAIM

The ornamental design for an artificial eyelash extension storage cartridge, as shown and described.

DESCRIPTION

FIG. 1 is an illustration of a front perspective view of an artificial eyelash extension storage cartridge;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top view thereof;

FIG. 7 is a bottom view thereof;

FIG. 8 is a bottom perspective view thereof.

The broken lines illustrate portions of the Artificial Eyelash Extension Storage Cartridge that form no part of the claimed design.

1 Claim, 6 Drawing Sheets
